(57) **CLAIM**

The ornamental design for a COMBINED CONTROLLER AND PHONE CASE as shown and described.

DESCRIPTION

FIG. 1 is a perspective view of a COMBINED CONTROLLER AND PHONE CASE, showing a left controller, a right controller, and a phone case;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is an exploded, perspective view thereof.

Broken lines are for illustrating portions of the COMBINED CONTROLLER AND PHONE CASE which form no part of the claimed design.

1 Claim, 7 Drawing Sheets
